Primary Examiner — W. A. Teddy Falloway(74) *Attorney, Agent, or Firm* — Bold IP, PLLC; Houda El-Jarrah(57) **CLAIM**

The ornamental design for a multi-chambered bottle, as shown and as described.

DESCRIPTION

FIG. 1 is a bottom perspective view of a multi-chambered bottle showing my new design;

FIG. 2 is a front view thereof;

FIG. 3 is a rear view thereof;

FIG. 4 is a left side view thereof;

FIG. 5 is a right side view thereof;

FIG. 6 is a bottom view thereof;

FIG. 7 is a top view thereof; and,

FIG. 8 is a view showing the multi-chambered bottle on a key chain holder.

The broken lines included in the Figures illustrate environmental structure and form no part of the claimed design. The multi-chambered bottle holds fluids in the three different chambers and can stand on its side or a cap.
